United States Patent Office

Des. 198,906
Patented Aug. 18, 1964

198,906

CHAIR

John E. McRee, Irving, Tex., assignor to Shampaine Industries, Inc., St. Louis, Mo., a corporation of Missouri

Filed Mar. 25, 1963, Ser. No. 74,101

Term of patent 3½ years

(Cl. D15—1)

FIG. 1 is a front perspective view of a chair embodying my new design; and

FIG. 2 is a rear perspective view thereof.

I claim:

The ornamental design for a chair, substantially as shown.
